(Cl. D61—1)

To all whom it may concern:

Be it known that we, Walter Dorwin Teague, Robert H. Ensign, Harold R. Beal and Murry N. Fairbank, citizens of the United States and residents, respectively, of Annandale, in the county of Hunterdon and State of New Jersey, Bronxville, in the county of Westchester and State of New York, Boston, in the county of Suffolk and State of Massachusetts, and Belmont in the county of Middlesex and State of Massachusetts, have invented a new, original, and ornamental Design for Photographic Camera or Similar Article, of which the following is a specification, reference being had to the accompanying drawings, forming part thereof.

Figure 1 is a front elevational view of a photographic camera or similar article, showing our new design;

Fig. 2 is a rear elevational view thereof;

Fig. 3 is a side elevational view thereof;

Fig. 4 is another side elevational view thereof;

Fig. 5 is a front elevational view with the bellows in extended position; and

Fig. 6 is a side elevational view with the bellows in extended position.

We claim:

The ornamental design for a photographic camera or similar article, substantially as shown.

WALTER DORWIN TEAGUE.

ROBERT H. ENSIGN.

HAROLD R. BEAL.

MURRY N. FAIRBANK.
